UNITED STATES PATENT OFFICE.

HENRY J. MESCHER, OF DAYTON, OHIO.

RADIATOR CAP.

Application filed November 12, 1926. Serial No. 147,897.

This invention relates to automobile caps and more particularly to that type of cap the body portion of which comprises two parts rotatably connected one to the other, one of said parts being adapted to be screwed onto the filling tube of a radiator and the other forming a support for the lid or closure.

One object of the invention is to provide a simple efficient means for rotatably connecting the two parts of the body portion.

A further object of the invention is to provide a latch for holding the lid in its closed position, which will be easy to operate and which will firmly hold the lid in its closed position.

Other objects of the invention will appear as the device is described in detail.

In the accompanying drawings Fig. 1 is a front elevation of a radiator cap embodying my invention; Fig. 2 is a plan view of the same; Fig. 3 is a section taken on the line 3-3 of Fig. 2; Fig. 4 is a section taken on the line 4-4 of Fig. 2; and Fig. 5 is a transverse section taken on the line 5-5 of Fig. 4.

In these drawings I have illustrated one embodiment of my invention and have shown the same as comprising a body portion consisting of a tubular member 1 and a collar 2. The tubular member 1 has on its lower portion threads 3 by means of which it may be attached to the filling tube of an automobile radiator. Near its upper end this tubular member has formed on the exterior thereof an upwardly facing circumferential shoulder 4 which is spaced a relatively short distance from the upper end of the tubular member. Formed in the upper surface of this shoulder is an inclined recess 5. The collar 2 is arranged about the upper end portion of the tubular member and has a forwardly extending circumferential rib 6 the lower surface of which rests upon the shoulder 4 and rotatably supports the collar on the tubular member. This rib has a vertical opening 7 extending through the same and a pawl 8 is loosely supported in this opening and is so arranged that when the collar is rotated on the tubular member to bring the opening 7 into line with the recess 5 the pawl will drop into the recess and so connect the two members that the rotation of the collar in one direction will cause the tubular member to rotate therewith, thus enabling the latter to be screwed onto the filling tube. When the collar is

rotated in the opposite direction the pawl will ride out of the recess, thereby permitting the collar to rotate with relation to the tubular member and preventing the latter from being removed from the filling tube. In order to retain the collar in position on the tubular member I have mounted within the upper portion thereof a sleeve 9 having at its upper end a flange 10 which extends outwardly over the upper end of the tubular member and over the upper edge of the rib 6 of the collar, and thus cooperates with the shoulder 4 to form a circumferential groove in which the rib rotates and which retains the collar in its proper position on the tubular member. The lower portion of the sleeve 9 is expanded, by spinning, swaging or the like, to press the same into gripping contact with the inner surface of the tubular member, the tubular member being preferably provided with a downwardly facing circumferential shoulder 11 on the inner surface thereof beneath which the lower portion of the sleeve engages when it is expanded, thus firmly securing the sleeve in position within the tubular member.

The collar 2 has at one side thereof a pair of pivot lugs 12 arranged to receive between them a pivot lug 13 carried by a lid or closure 14, the pivot lugs being connected one to the other by a pivot pin 15. A gasket 16 is preferably arranged within the upper portion of the collar, which extends above the tubular member, to provide a tight joint between the closure and the body portion of the cap. In order to hold the closure tightly in its closed position I have provided a latch which comprises a body portion or member 17 pivotally mounted between lugs 18 on that side of the closure opposite the lug 13. This pivoted member has a vertical bore or guideway 19 in which is slidably mounted a plunger 20, the upper end of which extends above the pivoted member and is provided with a head 21. The lower portion of the plunger is of reduced diameter, extends through the lower portion of the guideway and has secured thereto a locking member 22 having a hook shaped end adapted to engage beneath a correspondingly shaped projection 23 carried by the collar. A spring 26 acts on the plunger 20 to move the same upwardly and hold the locking member in contact with the projection or

keeper 23. Secured to the pivoted member 17 and, if desired, formed integral therewith, is a face plate 24 which extends below the guideway and has its inner surface arranged to contact with the outer end of the locking member 22 to guide this member and hold the same against rotation. This face plate also extends laterally beyond the sides of the pivoted member 17 and conceals all parts of the latch with the exception of the headed upper end 21 of the plunger. To release the latch the plunger 20 is depressed and the lower portion of the latch swung outward, this being easily accomplished with one hand by engaging the head of the plunger with the thumb and grasping the lower portion of the plate 24 with the finger. If desired, the lower portion of the plate may be provided with a finger piece 25.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

30 1. In a radiator cap, a tubular member

having a circumferential shoulder, a collar having a part engaging said shoulder to support said collar thereon, and a sleeve arranged within the upper portion of said tubular member, having at its upper end a flange overlapping said part of said collar to retain the same on said tubular member and having its lower portion expanded into gripping contact with said tubular member to retain said sleeve within said tubular member.

2. In a radiator cap, a tubular member having an exterior upwardly facing circumferential shoulder and an interior downwardly facing shoulder, a collar extending about said tubular member and having an inwardly extending rib engaging said exterior shoulder, the upper edge of said rib being adjacent to the upper end of said tubular member; and a sleeve arranged within said tubular member, having at its upper end a flange which extends across the upper end of said tubular member and the upper edge of said rib, and having its lower portion expanded into locking engagement with said interior shoulder.

In testimony whereof, I affix my signature hereto.

HENRY J. MESCHER.
